SIGNORS TO AMERICAN FIBRE CORPORATION, OF GARDNER, MASSACHUSETTS, A
CORPORATION OF MASSACHUSETTS

METHOD OF AND MECHANISM FOR WEAVING STAKE FABRIC

Application filed December 28, 1926. Serial No. 157,452.

This invention relates to a method of and mechanism for weaving, the mechanism being more especially adapted for laying picks of relatively stiff, coarse strand material such as 5 may be made from paper strips formed into cord or twine, and more particularly in the manufacture of what is known as "stake" fabric. In such fabric the strands running in one direction and known as "stakes" are 10 straight and spaced apart, the strands at right angles to the stakes being arranged in close array and crinkled to pass about the stakes. Often the stakes are of coarser and heavier material than the other strands. 15 Heretofore such stake fabric has been formed with the stakes as warp strands, the filling strands being beaten up together as the fabric is being formed, so that they are straightened laterally in the fabric, the ten- 20 sion on the warp strands which form the stakes acting to hold them straight.

It commonly happens, however, that it is desirable to have the stakes run crosswise of the fabric as it is used, and to provide sufficient length of strips under these conditions, wide looms have been necessary, the wide fabric being cut laterally into strips in which the stakes run crosswise.

Due to the nature of the strand material 30 and to the fact that it is commonly fed to the loom from spools so that it reaches the loom in more or less curved and crooked condition, looms designed to utilize stakes as warp strands are not adapted to use the stakes as 35 filling strands or picks, since the stakes are spaced from each other in the fabric and the beating action therefore does not have much straightening action on the strands. If straightening of the filling strands by other 40 than the beating could be insured, however, not only could the fabric be made with the stakes extending laterally and without the use of wide looms, but the weaving action would be very much faster due to the much 45 less number of stakes than of the crosswise strands in a unit of length.

According to the present invention, therefore, means are provided for insuring that the picks as laid spaced apart are straight in the 50 fabric so that these picks may be stakes. This

is done by the use of straightening devices acting on the stake to remove any tendency it may have to curve immediately prior to its being laid, together with means for applying tension thereto until its laying is completed. 55

For a more complete understanding of this invention reference may be had to the accompanying drawings in which—

Figure 1 is a fragmentary plan showing the pick laying needle in retracted position. 60

Figure 2 is a front elevation of the same.

Figure 3 is a detail plan of a pick gripper.

Figure 4 is a section on line 4—4 of Figure 3.

Figure 5 is a horizontal section on line 5—5 of Figure 6 through the strand cutter showing one end of the pick laying needle. 65

Figure 6 is a section on line 6—6 of Figure 5.

Figures 7 and 8 are a detail plan and elevation, respectively, of the strand straightening devices. 70

Figure 9 is a plan showing a stake fabric.

As illustrated in the drawings the picks are laid by means of a weft needle 10 comprising a tube having a strand passage 11 therethrough. This tube is fixed to a carriage 12 slidable along suitable ways 13 and is given a motion to project its free end 14 through the shed to carry with it the end of strand material, as will later appear and is then retracted so as to leave the shed, permitting the stake material grasped at the opposite end of the shed to pass through the strand passage. This motion of the needle may be accomplished by any suitable means, as shown in Figure 2, a shaft 141 having an actuating cam 15 thereon being provided, this cam acting on a follower 16 on a bell crank lever 17, one arm of which, as at 18, is connected through a link 19 to the carriage 12. 80

As shown best in Figures 7 and 8, the stake material extending through the needle passes through a guide eye 25 on the carriage 12 and in zigzag relation under and over a series of pins 26 projecting from one face of the carriage adjacent to the end portion 27 of the weft laying needle 10. The pins 26 being arranged so that the stake material must pass thereabout in zigzag formation, bend the ma- 85 90 95 100

terial back and forth and thus act as a straightening device for the stake to remove its tendency to curl or bend resulting from its having been wound on spools or reels. The flexing and reverse flexing of the stake material removes or greatly reduces its resilience so that upon being subsequently straightened under tension it will remain tolerably straight when the tension is removed. After leaving the last pin 26 the strand, shown at S, passes back of the spring pressed dog 28 having a relatively sharp end portion 29 which is held into engagement with the strand by any suitable means such as the spring 30, this dog acting so long as it is retained in its normally spring pressed condition, to prevent backward motion of the stake. The stake can be released, however, when this is desired, by pressing inwardly on the end 31 of the dog. After passing this dog 28 the stake extends into the weft laying needle 10 through its passage 11 and projects somewhat beyond its free end as shown best in Figure 5. The stake material lying in the weft needle is carried by the action of the cam 15 across the shed and its end is received between jaw elements formed as pivoted plates 35 which constitute the active parts of a stake gripper mechanism. The adjacent ends of these elements 35 are spring pressed toward each other, as by means of springs 36, and their adjacent edges are beveled as shown at 37, so that they take a close grip on the strand end presented thereto by means of the weft needle, the elements in gripping position being shown in Figure 4 in dotted lines. At 38 is shown a pair of guide plates so inclined as to direct the stake end into position between the plates 35.

The length of stake material lying within the stake passage has previously been acted upon by the straightening device comprising the pins 26 so that it lies in straight position with little or no lateral constraint within the needle channel 11, and as the needle retracts the stake is drawn through the needle, the straightening device straightening a length for a succeeding pick and imparting sufficient tension to the stake material so that it is retained in straight condition within the shed throughout the retracting motion of the needle. During the retracting motion of the needle, not only the stake in the shed is tensioned but also the adjoining portion which is passed by the pins 26 of the straightening device acting thereon. Thus the portion of the stake material which is bent back and forth by the pins 26 is immediately thereafter subjected to a stretching tension which completes the removal of its tendency to curve. As soon as the needle returns to its fully retracted position, means are provided for cutting off the stake inwardly of the free end of the needle and for releasing the gripper which has engaged the stake end. Both these

means, as shown, are actuated by the beater.

At 40 are shown portions of the beater mechanism. One of these portions carries the gripper elements 35 as shown in Figure 3, an angular bracket 41 being fixed to the beater 40 on one end and carrying the gripping mechanism at the other. The elements 35 of the gripping mechanism are pivoted between end plates 42 of a U shaped frame 43 which is directly fixed to the bracket 41. The bracket 41 has fixed thereto a guide bracket 44 through which passes a rod 45. To this rod is fixed a cross bar 46 carrying rods 47 which project through portions of the bracket 37 where they may impinge on the gripper elements 35 outwardly of their pivotal mounting so as to spread their adjacent ends 37 and release the strand. These ends 37 are beveled and as they do not come quite to alined relation when a stake is gripped, any pulling of the stake material as the weft needle retracts acts to tighten the grip of these jaws thereon. Movement of the member 46, however, acting to slide the rods 47 inwardly forcibly moves the grippers out of gripping relation. Such movement is accomplished as the beater starts to move forward in the beating operation by means of a cam follower 50 carried by the rod 45 which travels up an inclined stationary surface 51 as the beater moves forwardly. A spring 52 surrounding the rod 45 and bearing between the crossbar 46 and the bracket arm 41 acts to hold the rods 47 retracted so as to permit the jaws to come into clamping relation whenever the beater is in its back position as shown by dotted lines in Figure 3.

At the opposite end of the beater, at the side from which the weft needle moves into the shed, means are provided for cutting off each pick as laid. Such means as shown in Figure 5, comprise a blade member 60 carried by the beater 40, this blade 60 sliding across a stationary plate 61 having a slot 62 therein through which the weft needle passes as it enters and retracts from the shed. During the movement of the needle into the shed the blade 60 is in retracted position such that there is room between its cutting edge 621 and the inner edge of the slot 62 for the weft needle to pass. As the beater moves up, however, when the weft needle is in its retracted position, as shown in Figure 5, the plate 60 slides across the slot 62 and cuts off the pick just laid from the succeeding stake material. As the stake material at this time is under tension between the grippers 35 and the straightening pins 26 which exert a material resistance to its travel through the needle passage, there is a considerable length of stake material between the straighteners 26 and the knife blade 60 which is also under tension. As soon as the stake is cut this tension causes the end of the stake material projecting from the free end of the needle to be

pulled back slightly, the stake material then being relieved of its tension so that the cut end is drawn out of contact with the blade 60 as shown in full lines in Figure 5. The 5 backward motion of the beater does not, therefore, cause the projecting end of the stake to be bent back with the blade 60, as it might do if the cut end were not retracted therefrom by the release of the tension of the 10 stake within the needle passage. Should the end of the stake material be permitted to be much bent it might be moved out of position to be grasped by the grippers on the succeeding pick laying movement. After the beating 15 operation the work is fed a considerable distance when stake fabric is being made so as to space the stakes the desired distance apart.

As the stakes are straightened before being 20 laid and are held under tension after being laid until the beating operation, they remain straight in the fabric as illustrated at S in Figure 9. Reference to this figure will 25 show that these stakes are not closely positioned in the fabric and in the beating operation are not pressed up into contact with each other. Should the strand material not be straightened when laid or held under tension at that time, it might lie crooked in the fabric 30 as illustrated by the dotted lines in Figure 9, the beating operation itself being ineffective to straighten it since such beating does not cause the stakes to be pushed up together. It will be seen, however, that by reason of the 35 stakes being placed a considerable distance apart, the laying of each pick completes a much greater length of fabric than if the cross strands C illustrated in Figure 9 were used as filling strands, consequently the rate 40 of weaving is very materially increased, as the feed after each beating operation is greatly increased without a corresponding increase in the number of picks laid in a unit of time. The stakes also appear as the weft 45 of the fabric running crosswise of the length of fabric as it comes from the loom.

Having thus described this invention and having illustrated a mechanism embodying the same, it should be evident that various 50 changes and modifications might be made without departing from the spirit or scope of the invention as defined by the appended claims.

We claim:

55 1. In a machine of the class described, a weft laying mechanism comprising a needle having a strand passage, means to project one end of said needle through the shed and to retract said needle, and a series of pins at 60 the opposite end of said needle and about which the strand to be laid may pass in zigzag relation before entering said strand passage.

2. In a machine of the class described, a weft laying mechanism comprising a needle having a strand passage, means to project 65

one end of said needle through the shed and to retract said needle, a series of pins at the opposite end of said needle and about which the strand to be laid may pass in zigzag relation before entering said strand passage, and means for preventing retraction of said strand relative to said pins. 70

3. In a machine of the class described, a weft laying mechanism comprising a needle having a strand passage, means to project one end of said needle through a shed and to retract said needle, means for cutting off the picks from a contractile filling strand as laid by said needle, and means for exerting tension on said strand when it is cut, said means acting at a point adjacent to the other end of said needle in a direction away from the free end of the strand sufficient for the strand length therebetween to shorten as tension is released by the cutting so as to draw the cut 80 end out of contact with said cutting off means. 85

4. The steps in the method of weaving a stake fabric which comprise projecting the end of a strand of curving stake material of indefinite length through a shed, gripping and holding said end, simultaneously tensioning the portion of the stake within the shed and removing the curvature of the next adjoining portion of the material by reverse 90 flexure, closing the shed on the tensioned portion therein, and cutting off said portion within the shed. 95

5. The steps in a method of weaving stake fabric which comprise supplying a strand of indefinite length of stake material having a partially set curvature, removing from a portion of the strand of sufficient length to extend through the shed its tendency to curve, projecting said portion through the shed, 100 gripping the free end of said portion at the further side of the shed, then simultaneously tensioning the portion in the shed and operating on the next succeeding portion to remove its tendency to curve, closing the shed 105 on the portion therein, and cutting off said portion in the shed. 110

6. In a machine of the class described, a weft-laying mechanism comprising a needle having a strand passage, a carriage supporting said needle, means for actuating said carriage to introduce said needle into a shed and to retract it therefrom, and means for straightening and tensioning a portion of the strand passing through the needle during the 115 retractive movement thereof, said straightening means comprising gripping means positioned to seize the end of the strand carried by the needle, and a plurality of pins mounted on said carriage over which pins the 120 strands may pass in a zig-zag course. 125

7. In a machine of the class described, a weft-laying mechanism comprising a needle having a strand passage therein, means for reciprocating said needle into and out of a 130

shed, gripping means for seizing the free end of the strand carried by the needle, means for cutting the strand after the removal of the needle from the shed, a beater, and means operated by the motion of the beater to actuate said gripping means and said cutting means.

8. In a machine of the class described, in combination with means for laying a stake in a shed and a beater, mechanism for gripping the free end of the stake comprising a frame attached to said beater for motion therewith, a pair of jaws carried by said frame, means for pressing said jaws together, and means operable to open said jaws against the pressure of said jaw-closing means, said jaw-opening means comprising a cam follower carried by said frame and operatively connected to said jaws, and a fixed cam on which said follower moves with the motion of the beater.

In testimony whereof we have affixed our signatures.

JOHN E. MILLETT.
